HAIR-WAVING APPARATUS

Roy Baxter Gregory, La Fayette, Ind.

Application March 25, 1947, Serial No. 737,028

3 Claims. (Cl. 132--31)

1 The present invention relates to a new and improved method for waving hair on the human head and to apparatus for practicing the method. The so-called "permanent waving" of human hair is practiced extensively, and much progress has been made in improving the character and durability of the waves. The procedures which have heretofore been followed involve the winding of the hair on a spindle or mandrel and the stretching of the wound hair. The hair on the scalp is divided into a plurality of tresses, and each tress must be individually wound and stretched. The winding of the individual tresses of hair is very time-consuming and it is not uncommon for a patron of a beauty shop to spend several hours in obtaining a permanent wave. The stretching of the hair after winding must be done with a great deal of care and skill if the waves in the individual tresses are to be uniform in size and character. Present procedures also require the use of a clamp on each individual tress of hair adjacent to the scalp. These clamps are used in conjunction with the spindles or mandrels to enable the hair to be stretched and to hold the spindles or mandrels after the tresses are wound thereon. A large number of such clamps and mandrels are required for each head of hair to be waved. This necessitates an investment in equipment which is burdensome and which generally results in the equipment being unavailable except in established beauty shops.

It is a primary object of the present invention to overcome the foregoing difficulties and to provide a simple and effective method for the permanent waving of hair on the human head. A further object is to provide simple and inexpensive apparatus for carrying out the permanent waving operation. A still further object of the invention is to provide apparatus and a method for waving hair which permits the production of waves of uniform size and character. The waves produced with my method and apparatus are uniform not only as between the individual tresses of hair but also throughout the length of the individual tresses. Another object of my invention is to eliminate the need for winding and stretching the hair and to thus eliminate the poor results which are frequently obtained as a result of improper winding and stretching.

My method and the preferred form of apparatus will be described with reference to the accompanying drawing, wherein:

Figure 1 is a perspective view of one portion of the apparatus constructed in accordance with the present invention;

2 Fig. 2 is a perspective view of one of the plurality of rods which are used with the apparatus illustrated in Fig. 1.

3 Fig. 3 is an end elevation view illustrating the apparatus of Figs. 1 and 2 and demonstrating the method;

4 Fig. 4 is a fragmentary end elevation view of a modified form of the apparatus shown in Fig. 1;

5 Fig. 5 is a perspective view of a modified form of the piece of apparatus illustrated in Fig. 2.

The apparatus illustrated in Fig. 1 includes a plurality of parallel bars which are designated by the reference numerals 8, 11, 12, 13, 14, 15 and 16. Adjacent bars are joined to each other by resilient webs which are designated by the reference numerals 9, 17, 18, 19, 20 and 21. The bars are thus held in parallel side-by-side relationship and are spaced apart by distances less than the diameter of the bars. These webs form troughs between the adjacent bars and the resilient character of the webs permits limited separation of adjacent bars.

10 One of the rods which is used with the apparatus of Fig. 1 is illustrated in Fig. 2, and is designated by the reference numeral 10. The rods 10 are capable of being pressed between any adjacent bars into the trough between those bars. The diameter of the rods 10 should be equal to the diameter of the bars.

15 One of the end bars, for example the bar 16, is provided with a projection 22 at one of its ends and a similar projection 23 at its opposite end.

The reference numeral 24 in Fig. 3 designates **20** a tress of hair attached to the scalp which is designated diagrammatically at 25. The apparatus shown in Fig. 1 is positioned as shown in Fig. 3 with the bar 16 adjacent the scalp 25. The tress of hair 24 is passed over the top of the bar 16 between the projections 22 and 23. The tress of hair also extends over the top of the remaining bars of the apparatus. One of the bars 10 is then placed over the tress of hair, and is pressed downwardly between the bars 15 and 16 into the trough formed by the web 21. It has been pointed out above that the webs are resilient to an extent sufficient to permit the bars 10 and a portion of the length of hair 24 to be thus inserted into the trough. The web 21 causes the bars 15 and 16 to partially close over the rod 10. A loop is thus formed in the hair, which loop extends around the rod 10 which is positioned in the trough 21. Another rod 10 is then positioned over the tress of hair 24 between the bars 14 and 15. This rod 25 is pressed between the bars 14 and 15 into the

trough formed by the web 20. This procedure is repeated by working to the left as shown in Fig. 3 until the entire length of the tress has been formed into loops.

The hair should be moistened with a suitable waving lotion either before or after my apparatus is applied. It will be found easier in most instances to apply the waving lotion before placing the hair in the apparatus. The particular type of waving lotion which is used forms no part of the present invention, since there are several types of lotion available and it is unnecessary to describe the lotion in this application.

It will be seen from Fig. 3 that the wave can be extended quite close to the scalp. This is true largely because my apparatus does not require the use of clamps adjacent the scalp.

The bars 8, 11, 12, 13, 14, 15 and 16 and the rods 10 are illustrated in Figs. 1 to 3 as being of solid character. This is unnecessary, however, and in Fig. 4 I have illustrated bars 26 and 27 which are hollow or tubular. The bars 26 and 27 are connected by a resilient web 28. I have shown in Fig. 5 a rod 29 which is also tubular. It will be understood that the terms "bars" and "rods" when used in the specification and claims are intended to include the hollow or tubular members illustrated in Figs. 4 and 5.

The entire apparatus may be constructed of any suitable material which is not harmed by contact with the waving lotion. The apparatus may be of plastic material, in which case the entire assembly illustrated in Figs. 1 or 4 can be molded as a unit. The apparatus may be constructed of metal, in which case the webs are preferably brazed or welded to the bars. It is possible to construct the bars and the rods of paper tubes coated or impregnated with suitable moisture-proofing substances. As a general proposition, I prefer to make the apparatus as light as possible consistent with the necessary strength.

The apparatus may be constructed in a variety of sizes to meet the requirements of individual patrons and operators. The radius of curvature of the webs is preferably slightly greater than the radius of the rods 10 to provide an annular space between the rods and the webs to accommodate the hair.

After the waving lotion has imparted a permanent set to the waves, the hair is removed from the apparatus by removing the rods 10 from their respective troughs. It is preferable to remove the rods in reverse order of insertion.

My apparatus may be applied to the tresses of hair very promptly with a tremendous saving of time. The services of a skilled operator are not

necessary to obtain waves of permanent and lasting character.

Having thus described my invention, I claim:

1. Apparatus for use in the permanent waving of hair comprising a plurality of cylindrical bars disposed in parallel side by side relationship and spaced apart by distances less than their diameter, resilient arcuate webs joining adjacent bars, and a plurality of cylindrical rods of a diameter approximately equal to the diameter of said bars, said rods being arranged to engage a tress of hair and to pass with an increment of the length thereof between adjacent surfaces of said bars into the concavity of said arcuate webs, said webs causing said bars to partially close over said rods.

2. Apparatus for use in the permanent waving of hair comprising a plurality of similar cylindrical bars disposed in parallel side by side relationship, resilient arcuate webs joining adjacent bars and resiliently retaining said bars spaced apart by distances less than the diameter of said bars, said webs being joined to said bars in such manner that adjacent surfaces of said bars provide shoulders partially closing the entrances to said arcuate webs, and a plurality of similar cylindrical rods of a diameter approximately equal to the diameter of said bars, said rods being arranged to engage a tress of hair and to pass with an increment of the length thereof between said shoulders into the concavity of said webs, said webs causing said shoulders to partially close over said rods.

3. Apparatus for use in the permanent waving of hair comprising a plurality of similar cylindrical bars, means for resiliently holding said bars in parallel side by side relationship and spaced apart by distances less than their diameter, and a plurality of similar cylindrical rods of a diameter approximately equal to the diameter of said bars, said resilient holding means permitting said bars with increments of the length of a tress of hair thereon to pass between adjacent bars whereupon said means causes said bars to partially close over said rods.

ROY BAXTER GREGORY.
